UNITED STATES PATENT OFFICE.

CHARLES H. BLAU AND GEORGE W. KELLY, OF COLUMBUS, GEORGIA.

CORE-MAKING MACHINE.

No. 886,927.

Specification of Letters Patent.

Patented May 5, 1908.

Application filed July 11, 1906. Serial No. 325,595. Renewed November 4, 1907. Serial No. 400,552.

To all whom it may concern:

Be it known that we, CHARLES H. BLAU and GEORGE W. KELLY, residing at Columbus, in the county of Muscogee and State of 5 Georgia, have invented certain new and useful Improvements in Core-Molding Machines; and we do hereby declare the following to be a full, clear, and exact description of the invention, such as will enable others 10 skilled in the art to which it appertains to make and use the same.

This invention relates to machines used in metal foundries for molding cores by expressing sand through suitable dies; and it consists in the novel construction and combination 15 of the parts hereinafter fully described and claimed.

In the drawings, Figure 1 is a longitudinal section through the machine. Fig. 2 is an 20 end view showing the support for the core tray in section. Fig. 3 is a view of the opposite end of the machine from that shown in Fig. 2, and showing the hub of the fly-wheel in section.

25 A is the hopper in which a mixture of sand with other ingredients, suitable for forming cores, is placed. B is the sand chamber below the said hopper. The chamber B is provided with a clamp C at one end and this 30 clamp is preferably cylindrical. The clamp is split upon one side, and it is provided with lugs b and a clamping screw c.

D is a die having an enlargement d at one end which is adjustable longitudinally in the 35 clamp C. When the position of the die has been adjusted it is clamped to the sand chamber by means of the clamping screw and clamp. E is a revoluble sleeve which is journaled in bearings e at the other end of the 40 said chamber from the die, and which is provided with a rectangular driving socket e'.

F is the packing-screw which is provided with a rectangular driving projection f which is 45 slidable in the socket e'.

F' is a thrust screw which engages with the end portion of the sleeve and which bears against the end of the projection f so that the 50 position of the packing-screw may be adjusted.

55 The packing-screw extends through the sand chamber and projects partway through the die. A vent former f'' is secured centrally of the said packing-screw in the other end portion of the die, and it consists of a small rod. The packing-screw and its die are made of various sizes to form cores of

corresponding size, and all the dies have similar enlargements d which are adjustable in the clamp C.

G is a toothed pinion secured on the sleeve 60 E, and g is a toothed wheel which gears into the pinion G. The wheel g is secured on the hub h of a fly-wheel H, and the said hub is journaled on a pin h' which projects from the supporting base B' of the sand chamber B. 65

i is a handle which is mounted on an arm i which is provided with a clutch member j. This clutch member engages with a similar clutch member j' formed on one side of the fly-wheel. 70

J is a thumb-screw which holds the two clutch members in engagement with each other, and which permits the arm and handle to be adjusted so that the handle may be placed at different distances from the center 75 of the fly-wheel, according to the resistance of the sand in the machine.

K is a tray or plate for receiving the cores which are expressed from the die. This tray is secured to a supporting bracket k which is 80 slidable longitudinally upon a guide k'. This guide is arranged in an inclined position, and it is secured to the base B' below the die.

L is a bolt provided with a thumb-nut for securing the bracket to the guide. The 85 guide is preferably provided with two parallel tracks or bars upon which the base of the bracket is slid able, and the clamping bolt is arranged between the said bars.

The tray is adjusted to the die by sliding 90 the bracket on the guide to the position shown in the drawings.

The core-sand is fed from the sand chamber into the die by the screw which packs it in the die. The density of the core depends 95 upon the length of the space x between the end of the packing screw and the delivery end of the die. When the length of this space is increased the frictional resistance of the sides of the die to the sand is also increased, and the core is consequently more dense. Various mixtures of sand with other materials are used to form the core-sand according to the size of the core and the use to which it is to be put, and it is very important 100 to be able to form the cores of any prearranged density.

The length of the consolidating space x is varied by sliding the die in the clamp before securing it by the clamping screw. A finer 110 adjustment of the space x is obtained by means of the screw F' which slides the pack-

ing-screw to a limited extent in the die, and this adjustment may be effected at any time without unclamping the die.

What we claim is:

- 5 1. In a core molding machine, the combination, with a sand chamber provided at one end with a clamp, of a die adjustable longitudinally in the said clamp, a driving-sleeve journaled at the other end of the said chamber and provided with means for revolving it, a packing - screw operatively engaging with the said sleeve and projecting through the said chamber and engaging with the said die, and an adjusting screw bearing against 15 the end of the said packing-screw and engaging with the end of the said sleeve.
2. In a core molding machine, the combination, with a sand chamber provided with a die at its front end, of a driving sleeve journaled at the other end of the said chamber and provided with means for revolving it, a packing-screw operatively engaging with the said sleeve, and a screw for adjusting the said packing-screw longitudinally, engaging 25 with the end of the said sleeve and bearing endwise against the said packing screw.
3. In a core molding machine, the combination, with a sand chamber and a die at one end thereof, of a sleeve journaled at the 30 other end of the said chamber and provided with a driving device, a packing screw working in the said chamber and die and also pro-

vided with a rectangular portion slidable longitudinally in engagement with the aforesaid driving device, a thrust-screw engaging 35 with one end of the said sleeve and bearing endwise against the packing-screw for adjusting the position of the said packing-screw in the said die, and means for revolving the said sleeve.

4. In a core molding machine, the combination, with a sand chamber, a die secured thereto, and a revoluble packing-screw working in the said chamber and die; of an inclined guide secured to the said sand chamber, and a support for receiving the core from the said die adjustable on the said guide. 40 45

5. In a core molding machine, the combination, with a sand chamber, a die secured thereto, and a revoluble packing-screw working in the said chamber and die; of an inclined guide secured to the said sand chamber, a supporting bracket adjustable on the said guide and provided with a fastening device, and a core-receiving tray carried by the 50 55 said bracket.

In testimony whereof we affix our signatures, in presence of two witnesses.

CHAS. H. BLAU.
GEO. W. KELLY.
